UNITED STATES PATENT OFFICE.

HARRY R. FURROW, OF PIQUA, OHIO.

TOY.

1,133,719.

Specification of Letters Patent.

Patented Mar. 30, 1915.

Application filed May 19, 1914. Serial No. 839,606.

To all whom it may concern:

Be it known that I, HARRY R. FURROW, a citizen of the United States, residing at Piqua, in the county of Miami, State of Ohio, have invented certain new and useful Improvements in Toys; and I do hereby declare the following to be a full, clear, and exact description of the invention, such as will enable others skilled in the art to which

10 it appertains to make and use the same.

This invention relates to improvements in toys and has for an object to provide an extremely simple and inexpensive device that will prove both amusing and attractive and one which may be used and enjoyed by the smallest child.

With the above and other objects of similar nature in view, the invention consists in the construction, combination and arrangement of parts set forth in and falling within the scope of the appended claim.

In the drawings: Figure 1 is a side elevation of the improved toy, Fig. 2 is a plan view thereof with the spindle shown in section, Fig. 3 is a vertical sectional view taken on the line 3—3 of Fig 1, and Fig. 4 is a fragmentary sectional view on the line 4—4 of Fig. 2.

Referring now more particularly to the drawing, the improved toy comprises the spindle 10 which is spirally threaded as at 11, and has its ends reduced and threaded as at 12 for the purpose to presently appear.

Mounted for rotation on the spindle 10 and adapted to travel therealong on the spiral threads 11, is a disk 13 said disk being preferably stamped from a blank of sheet metal such as tin or the like and being formed on its periphery with the apertured ears 14. Suitably arranged in the center of the disk and threaded to receive the spiral threads 11 of the spindle is a tap 15 the upper and lower faces of which are rounded as at 16. Taps 17 are also provided on the reduced portions 12 of the spindle and formed with rounded faces 18, these faces presenting a limited bearing surface to the tap 15 and prolonging the rotation of the disk when same is at its limit of movement 50 in either direction on the spindle.

Passed through the openings in the ears 14 are bolts 19 on which are loosely mounted for rotation the fans 20, sleeves 21 being likewise mounted on the bolts and spacing said fans from the disks 13. It will be noted 55 that diametrically opposite pairs of fans are directed oppositely from the disk 13, thereby insuring rotation of one of said pairs irrespective of the direction of movement of the disk. There is further provided at each 60 end of the spindle 10, a stand 21' whereby the toy may be supported upon the floor or the like in a substantially vertical position, said stand being internally threaded as at 22 to receive the reduced portion 12 of the 65 spindle.

The operation of the device is obvious, the toy being placed in position as above-described, the disk 13 gravitates along the spindle 10, rapid rotation being imparted to 70 the disk by the spiral threads 11. It is thus apparent that a sufficient current of air will be created to effect the rotation of one pair of fans 20, the spindle 10, when the disk has reached its limit of movement in one 75 direction, being inverted and rotation of the disk and the other pair of fans effected in a similar manner.

Should it be desired, the toy may be rendered more attractive by painting the spindle, disk and fans in various colors, these colors blending during the rotation of the disk and producing an effect that will please and attract the child.

What is claimed is:

In a toy, the combination with a spirally threaded spindle, of a disk rotatably mounted upon said spindle and adapted to travel therealong, and fans loosely carried by the disk and adapted for rotation during movement of said disk with respect to the spindle.

In testimony whereof, I affix my signature, in the presence of two witnesses.

HARRY R. FURROW.
